UNITED STATES PATENT OFFICE

2,048,034

HAMMER

Raymond F. Schiveley, Houston, Tex.

Application April 18, 1934, Serial No. 721,202

1 Claim. (Cl. 1—45)

This invention relates to a hammer.

An object of the invention is to provide a hammer particularly designed for driving tacks, or short nails, and equipped with a magazine for holding the tacks and manually operable means whereby the tacks may be delivered singly from the magazine to the hammer head.

Another object of the invention is to provide a hammer having a magnetic head whereby the tack delivered thereto will be held in position for driving said hammer—also having a magazine for holding the tacks in readiness to be delivered to the head and manually operable means for delivering the tacks to the head singly and in succession as the tacks are driven.

With the above and other objects in view, the invention has particular relation to certain novel features of construction, operation and arrangement of parts, an example of which is given in this specification and illustrated in the accompanying drawing wherein:

Figure 1 shows a side elevation of the hammer showing the delivery mechanism in the position it will occupy at the end of the delivery movement.

Figure 2 shows a cross sectional view taken on the line 2—2 of Figure 1.

Figure 3 shows an end view.

Figure 4 shows a fragmentary side elevation, showing the hammer in tack driving position.

Figure 5 shows a bottom view of Figure 4.

Figure 6 shows a fragmentary view of the hammer taken at right angles to the view shown in Figure 1, and

Figure 7 shows a fragmentary sectional view showing the main spring and casing therefor.

In the drawing the numeral 1 designates the handle having the head 2 secured to one end thereof. This head may have a weight 3 removably secured thereto to give the hammer the desired momentum. The driving end of the head is slotted as at 4 to form said end into the design of the ordinary horse shoe magnet.

There is an arcuate magazine 5 whose outer end is attached to the clamp 6. This clamp embraces the handle 2 and is suitably secured thereto. The forward end of the magazine, adjacent the hammer head, is attached to a bracket 7 which is also secured to said handle. The magazine is channel shaped having its margins overturned toward each other and spaced apart to provide a dovetailed groove 8 to receive the heads of the tacks and also providing the longitudinal slot 9 between said overturned margins

along which the tacks may pass as delivered from the magazine.

Suitably secured to the handle there is a spring housing 10, preferably of cylindrical contour and in this housing there is a main spring 11, coiled about the cross pin 12. One end of the spring 11 is attached to the housing and the other end is attached to the cross pin 12 which is rotatable in the housing. This cross pin has a spool 13 fixed thereon. Suitably mounted in the magazine there is a pusher 14 having the outstanding fin 15 which works in the slot 9. The fin 15 has a lateral lug 16 and one end of the steel tape or ribbon 17 is attached to said lug and the other end of said tape works through a slot in the housing 10 and is wound on the spool 13. When the magazine is filled with tacks as 18 the tension of the spring 11 acting through the tape 17 urges the pusher 14 against the assembly of tacks in the magazine.

Secured to the bracket 7 there is a flexible arm 19 whose free end has the inwardly turned lug 20, Figure 5, which terminates in a finger 21 and this finger normally engages in front of the tack to prevent the discharge of the tacks from the magazine.

Pivottally mounted on the hammer head there is a yoke comprising the side arms 22, 23, which are connected by the cross bar 24. These side arms embrace the head 2 and their free ends are capable of being flexed outwardly as will be hereinafter explained.

Pivottally mounted on the handle adjacent the grip end thereof there is a lever 25 whose free end is formed with a finger grip 26. A link 27 is pivoted at one end to the arm 23 of said yoke and is pivoted at its other end to the lever 25.

In use the cross head 14 may be retracted or moved outwardly clear of the outer end of the magazine and the magazine may then be loaded or filled with tacks and the cross head then reinserted into the outer end of the magazine. The spring 11 is under tension and the forward tack in the magazine will be therefore held in yieldable engagement with the finger 21. The user of the hammer may then engage the finger grip 26 and retract the lever 25 into the position shown in Figure 4 thus pulling the yoke rearwardly. The free end of the arm 23 has an external knob 28 and when the lever 25 is retracted this knob will engage the inner side of the flexible arm 19 and force the same outwardly releasing the finger 21 from the forward track in the magazine. The free ends of the arms 22, 23 are inwardly turned forming the grip jaws 29, 30 Figure 6, at the

driving end of the hammer the said jaw 30 terminating in the engaging finger 31. At the time the forward tack is released by the finger 21, the finger 31 engages said tack and the jaw 30 is forced outwardly and finger 31 passes by said tack and the flexibility of the jaw 30 causes said finger 31 to engage behind the tack so released as illustrated in Figure 5, and jaws 29, 30 engage and grip said tack. Upon engagement of the forward tack by the finger 31, as above stated, the forward tack will be slightly tilted rearwardly, causing its head to bind or wedge in the magazine, setting up sufficient resistance against the impact of the jaws 29, 30, to prevent the series of tacks from being forced back along the magazine. The lever 25 is then moved forwardly carrying the yoke back into its original position. When the arm 19 is released by the knob 28 the finger 21 will move in front of the next succeeding tack, so as to retain the remaining tacks in the magazine. The driving end of the hammer has the rearward extensions 32 whose outer sides are outwardly flared and as the arms 22, 23 move back over said outwardly flared extensions, the arms 22, 23 are spread apart as shown in Figure 3 to release the tack. While the tack is being moved from the magazine, the flexible spring 33 bears against the head of the tack so as to return the tack from its tilted to its upright position and to force said head closely against the jaws 29, 30 and to cause it to clear the extensions 32. The tack will be held in position for driving by the magnetic influence of the hammer head and the lever 25 may then again be retracted to the position shown in Fig-

ure 4 and the tack may then be driven. The succeeding tacks of the magazine may be released in a similar manner in the process of driving the tacks.

This type of hammer is particularly useful in tacking up canvas on walls and in like places in carrying on the work of paper hanging and for similar purposes.

The drawing and description disclose what is now considered to be a preferred form of the invention by way of illustration only, while the broad principle of the invention will be defined by the appended claim.

What I claim is:

A hammer for driving nails and the like having a handle and a driving head, a magazine on the handle shaped to retain an assembly of nails and to permit the assembly to move longitudinally along the magazine, a pusher, means normally urging the pusher against the assembly to affect the discharge of the nails from the magazine, a yieldably mounted releasable retainer normally preventing such discharge, a yoke pivotally mounted on the head comprising flexible side arms formed with inwardly turned gripping jaws 25 thereon, manually operable means for moving said side arms and jaws into position to release the retainer from the nail assembly and to thereafter engage the released nail, said jaws being formed to engage and grip the released nail, and means for moving said jaws to another position to release the retainer and to deliver the discharged nail to the driving end of the hammer.

RAYMOND F. SCHIVELEY.
